UNITED STATES PATENT OFFICE

152,369

DESIGN FOR A SMOKER'S PIPE

Merrill G. Sampson, Santa Monica, Calif.

Application May 11, 1948, Serial No. 146,278

Term of patent 14 years

(Cl. D85—8)

To all whom it may concern:

Be it known that I, Merrill G. Sampson, a citizen of the United States, residing at Santa Monica, in the county of Los Angeles and State of California, have invented a new, original, and ornamental Design for a Smoker's Pipe, of which the following is a specification, reference being had to the accompanying drawing, forming part thereof.

The dominant features of my design reside in those portions shown in full lines.

I claim:

The ornamental design for a smoker's pipe, substantially as shown and described.

MERRILL G. SAMPSON.
